United States Patent Office

Des. 228,592
Patented Oct. 16, 1973

228,592

CHAIR

Eugene J. Costabile, Oak Lawn, Ill., assignor to Mohasco
Industries, Inc., Amsterdam, N.Y.

Filed Nov. 26, 1971, Ser. No. 202,739

Term of patent 14 years

Int. Cl. D6—01

U.S. Cl. D6—39

The figure is a perspective view of a chair illustrating my new design. The back of the chair is conventionally plain while the side not shown is substantially identical to the side shown.

I claim:

The ornamental design for a chair, as shown and described.
